UNITED STATES PATENT OFFICE.

JOHN MEISSNER, OF NEW YORK, N. Y., ASSIGNOR TO HIMSELF AND HENRY FLEISCHMAN, OF SAME PLACE.

CAR-BRAKE.

SPECIFICATION forming part of Letters Patent No. 242,673, dated June 7, 1881.

Application filed March 14, 1881. (No model.)

To all whom it may concern:

Be it known that I, JOHN MEISSNER, of the city, county, and State of New York, have invented a new and useful Improvement in Car-
5 Brakes, of which the following is a specification.

The invention is designed as an improvement on the car-brake for which Letters Patent No. 214,418 were issued to me April 15,
10 1879; and its object is to simplify and reduce the cost of the operating parts of a brake that will apply as well to the car-wheels when running on curves as when running on a straight line.

15 The invention consists of a horizontal frame having bowed or curved end bars and provided with side sockets for holding the brake-shoes, said frame being held in position against the bottom of the car by longitudinally-movable end clamps or racks in such manner that it is free to accommodate itself to the relative positions of the wheels on curves in the road, said clamps or racks being connected with brake-rods or shafts, whereby said frame may
20 be moved longitudinally for applying or turning off the brake; and it consists, further, of a device for preventing the accidental setting of the brake when the car is running on a curve, where the rails on one side of the track are
25 higher than on the other side, all of which will be hereinafter described.

Figure 1 is a reverse plan view, with parts broken away to exhibit other parts, showing the improved device in position on the bottom
35 of a car. Fig. 2 is a partly sectional side elevation of the same, with parts broken away to exhibit other parts on line $\alpha\alpha$, Fig. 1. Fig. 3 is a sectional end elevation of the same. Fig. 4 is an end elevation, showing the device for
40 preventing the accidental setting of the brake.

Similar letters of reference indicate corresponding parts.

In the drawings, A represents a car-floor; B, the truck-frame; C, a car-axle, and D the car-wheels. A bolt, E, passing down through the car-floor A, centrally through a circular anti-friction plate F, through a strut, G, and truck-frame B, and having a nut, a, on its end, holds these parts together and in position. Angle-lugs H, bolted on the cross-bar of the frame

B, have their upper ends in contact with the anti-friction plate F, and thereby afford bearing-points for steadyng the frame B when the car is in motion.

L is the brake-shoe frame having straight 55 parallel sides b and bowed ends c, as shown, and having in each of its sides two sockets, m, for holding the brake-shoes M, said sockets m having hinged outer sides, n, that may be thrown open for the placing or removal of 60 the shoes M, and that are secured closed in place by screw or other device, as shown at o.

On the under side of the car-bottom A, near the front thereof, a bolt, p, holds a plate, N, by passing through the longitudinal slot p' of 65 the latter. Said plate N is toothed on one edge, as shown at q, thus forming a rack whose teeth engage with a pinion, O, that is held by a lug, o', on the car-bottom A. This plate N is provided on its inward end with two downward-projecting screws or lugs, q', that hold the forward bowed end, c, of the brake-shoe frame L between them in such a manner that said front end of the frame L is thereby held up in position, while at the same time it can swing in a 70 horizontal plane sufficiently to accommodate itself to the position of the car-wheels D as they move on a curve of the road. The pinion O is keyed on the lower end of a brake-shaft, P, which is provided with the usual handle or 75 wheel P'. The rear end, c, of the brake-shoe frame L is held between lugs r, that project downward from an angle-plate, Q, that is screwed on the end of a connecting-rod, Q', that is held upon the under side of the car-bottom A centrally and longitudinally by a box or clamp, Q², as shown, the opposite end of 80 said connecting-rod Q' being attached to a like plate, Q, that pertains to the brake attachment of the rear truck of the car. 85

The wooden brake-shoes M, which are cut out on their lower edges to correspond, or nearly so, with the curves of the peripheries of the car-wheels D, are provided with broad metallic caps s s to strengthen and make them 95 more durable, and when inserted in the sockets m of the frame L these caps s rest on the upper edges of the sockets m, and the shoes M are thereby held just above the rims of the wheels D. 90

To the inner face of the frame L, on the 5
sockets m are rigidly secured depending angle plates or guards T, that reach nearly to, but are not in contact with, the axles C. When
the car A is running on a curve where one side
of the track is higher than the other, the higher
ends of the axles C will press upward against
the bottoms of the two guards T on that side, and thereby elevate the frame L and the brake-
shoes M on that side, and thus prevent the
braking of the wheels D, which would otherwise occur, there being also, as parts of this
preventative device, yokes U, holding elastic
springs V on top of the caps s, which yokes U
have their ends slotted, as shown at x, Fig. 4,
and engaged over the projecting ends of the
caps s, so that said yokes U can move freely
up and down with the elastic movements of
the springs V. These springs V serve, by their
elasticity, not only to keep the car-body in a
horizontal plane when running where one side
of a track is higher than the other, but serve
also to prevent any sudden jar as the axles C
come in contact with the guards T.
To set the brakes power is applied to the
brake-shaft P to turn the pinion O in either
direction, as the case may be, and this motion
and force are transmitted through the rack N,
and thence directly to the brake-shoe frame L,
so that the said frame L is moved longitudinally,
and thereby forces the brake-shoes M in
contact with the rims of the car-wheels D,
wedging said shoes M at the same time be-
tween the rims of said wheels D and the bot-
tom A of the car. In this position said shoes
M brake the wheels D effectively, in which
matter the force applied to the brake-shaft P
is supplemented by the weight of the car upon
the upper surfaces of said yokes U, and there-
40 by upon the brake-shoes M. Consequently it
is obvious that the greater the weight of the
car and its load the greater will be the influ-
ence they exert in braking the wheels.

As the frame L is free to swing within cer-
tain limits between the lugs q' r, and as the
brake-shoes M extend below and outside the
flanges of the wheels D, it follows, when the

car is running on a curve, that the wheel-flanges
will bear against the sides of said shoes M, and
thereby keep them and the frame L in the 50
same relative position with the wheels D, so
that said wheels D can be braked as readily
when running on a curve as when running on
a straight line.

R represents the rubber buffers or cushions, 55
held in the truck-frame B above the journal-
boxes S, that support the ends of the axle C.

Having thus described my invention, I claim
as new and desire to secure by Letters Patent—

1. A car-brake constructed substantially as 60
herein shown and described, consisting of the
brake-shoe frame L, provided with side sock-
ets, m, brake-shoes M, and longitudinally-
movable plates N Q, provided with lugs q' r,
held against the bottom of the car, and ar- 65
ranged as set forth.

2. In a car-brake, the combination, with the
brake-shoe frame L, of the hinged socket sides
n, substantially as and for the purpose de- 70
scribed.

3. In a car-brake, the combination, with the
movable brake-shoe frame L, of the slotted and
toothed plate or rack N, provided with lugs q,
substantially as herein shown and described,
whereby longitudinal motion is transmitted to 75
said frame, as set forth.

4. In a car-brake, the combination, with the
brake-shoe frame L and shoes M, of the guards
T, substantially as herein shown and described,
whereby the said shoes are prevented from ac- 80
cidentally braking the car-wheels, as set forth.

5. In a car-brake, the combination, with the
brake-shoe frame L and shoes M, of the yokes
U and springs V, substantially as herein shown,
and for the purpose described. 85

6. In a car-brake, the combination, with the
brake-shoe frame L and shoes M, of the guards
T, yokes U, and springs V, substantially as
herein shown, and for the purpose described.

JOHN MEISSNER.
